UNITED STATES PATENT OFFICE.

FRANK E. MINER, OF CHICAGO, ILLINOIS.

PORTABLE TURNTABLE.

Application filed August 12, 1922. Serial No. 581,397.

To all whom it may concern:

Be it known that I, FRANK E. MINER, a citizen of the United States, residing at Chicago, in the county of Cook and State 5 of Illinois, have invented certain new and useful Improvements in Portable Turntables, of which the following is a specification.

This invention relates in general to turntables, and has more particular reference to 10 a turn table of the portable type, which, while capable of many uses, is particularly adapted for road construction work.

In the building of concrete roads, the 15 gravel and cement which are mixed together with water in a mixer and delivered therefrom in plastic condition to be spread upon the roadway, are, under modern practice, hauled to the mixer in trucks. Since the 20 prepared roadway upon which the concrete is to be laid is relatively narrow, considerable difficulty is encountered and much time is lost by the trucks in turning around on this roadway in front of the mixer, partic- 25 ularly in view of the fact that the turning is done while the trucks are still loaded in order that they may be backed up to the proper position in front of the mixer and dumped.

30 One of the primary purposes of my present invention is to provide a turntable which may be set at any desired distance in front of the mixer upon the roadway, and upon which the loaded trucks are driven, where- 35 upon the turntable is swung through an arc of 180 degrees, turning the truck end for end so that it may then be backed off and un- loaded.

Another object of my invention is to pro- 40 vide a turntable for the purpose indicated which can be easily operated with a loaded truck thereon, and which, when desired, can be moved forward upon the roadway and can be readily transported from place to 45 place when necessary.

A further purpose is to provide a turn- 50 table which will be simple in construction, strong and durable in operation, one which can be economically manufactured, and one 55 which will occupy only a portion of the roadway so as to permit the trucks which have discharged their loads to drive away from the mixer alongside the turntable, instead of over the turntable as is necessary with some now on the market.

Other objects and advantages of this in-

vention should be readily appreciated as the same becomes better understood by reference to the following description when considered in connection with the accompanying drawings.

Referring to the drawings:

Fig. 1 is a plan view of a turntable embodying my invention, the position of a truck thereon being shown in dotted lines; 65

Fig. 2 is a side elevation of the turntable; and

Fig. 3 is a sectional view on the line 3—3 of Fig. 1.

Referring to the drawings more in detail, 70 it will be observed that the turntable body comprises a wheel mounted frame consisting of two longitudinally extending side rails or track members 5 and 6 connected together at intervals to form a rigid construction by 75 means of a series of cross members 7 and the drop axle 8. The front is further strengthened by a cross channel member 9, as shown.

The track members may be of steel con- 80 struction, if preferred, although I have shown for illustrative purposes, a construction comprising the channel side irons 11 tied by rods 12 to inner wooden members 13 and between which are disposed heavy planks 14 forming the tracks proper upon 85 which the wheels of the truck run. To ensure against the truck wheels sliding off from the track members, I prefer to provide upwardly extending flange members 15 and 16 disposed preferably at the inner edge of 90 each track member.

The rear axle 8 is shaped as shown in Fig. 3 and a supporting wheel 17 is journaled at each end thereof. The upwardly extending extensions 18 on the axle serve as struts for 95 the strengthening tie rods 19 connected at one end to these struts and at their opposite ends to the frame structure.

The forward end of the turntable body is carried by an axle 21 connected to the 100 body by I-beams 22, this axle being equipped at each end with a knuckle 23 upon one arm of which is mounted a front wheel 24. The other arm of each knuckle has a link 25 pivotally connected thereto and for transportation purposes the inner ends of these links are brought together and connected by a pin 26 to a steering lever or handle 27 fulcrumed on the channel member 9. When thus connected, the wheels are 105 disposed in parallel relation, as indicated in dotted lines in Fig. 1, and the apparatus 110

may be steered like an automobile by manipulation of the lever 27. When, however, the apparatus is in use, the links 25 are disconnected and their inner ends are connected 5 by bolts 28 to the channel member 9 so as to dispose the wheels 24 in the position shown in full lines in Fig. 1, so that they will travel in an arc about a supporting axis located slightly forwardly of the rear axle, as 10 will be now described.

A pair of heavy cross beams 31 extend transversely of the frame structure just forwardly of the rear axle and carry a downwardly projecting round headed swivel bolt 15 32, best shown in Fig. 3. The round lower end of this bolt or pin engages in a socket formed in a block 33, the pin being held against withdrawal from this socket by retaining plates 34 securely bolted to the block. 20 The block is supported by wedges 35 driven beneath the same a sufficient distance to lift the wheels 17 clear of the roadway, as shown in Figs. 2 and 3.

When the turntable has been moved to 25 the desired position, the wedges are driven under the block 33 to lift the rear wheels 17 clear of the ground, and the front wheels are disconnected from each other and turned into the position shown in full lines in Fig. 30 1, in which position they are secured by fastening the links 25 to the member 9 by the pins 28 as previously explained. The rear end of the turntable is now disposed away 35 from the mixer in position to receive a loaded truck. The truck is then driven onto the turntable and as the wheels travel onto the rear end of the turntable tracks, the forward end of the turntable may be lifted slightly 40 from the ground, which, however, will do no harm. The truck is driven onto the turntable until its front wheels abut against a stop member 36, whereupon the brakes will be set to retain the truck in position. When 45 properly positioned on the turntable, the center of gravity of the truck is disposed substantially over the swivel pin 32 so that practically the entire weight of the turntable as well as the truck, is carried by the block 33 leaving but little weight upon the front 50 wheels 24. The front end of the turntable may then be pushed laterally by hand, turning the same upon the pin 32 as an axis, the wheels 24, by reason of their position, traveling in an arc about this pin as a center. 55 When the turntable and the truck thereon have been turned through an arc of 180 degrees, the truck may be backed off the turntable toward the mixer where it will be dumped. After the truck has been unloaded, 60 it may be driven away from the mixer alongside the turntable which, when disposed endwise upon the roadway, occupies less than half of the roadway. The turntable is then swung back into receiving po-

sition for the next truck and the operation is repeated for each truck to be unloaded.

During the turning operation, the rear wheels 17 are normally clear of the roadway, but if the turntable should tilt laterally upon its pivot pin, such tilting movement will be limited by the engagement on that side of the apparatus of the rear wheel with the roadway, whereby the apparatus is prevented from tipping over. 75

It is believed that my invention, its construction and mode of operation, and many of its advantages will be understood from the foregoing without further description, and while I have shown and described a preferred embodiment thereof, obviously the details of construction may be varied within wide limits without departing from the scope of the invention as defined in the following claims. 80

I claim:

1. In a portable turntable, the combination of a platform adapted to receive a truck, rear wheels for said platform, means for pivotally supporting said platform in proximity to the center of gravity of a truck thereon so as to dispose said rear wheels clear of the ground, and front wheels for said platform adapted to be disposed in substantial parallelism for transportation purposes and to be positioned to travel in an arc about said pivotal support as a center for turning purposes. 90

2. In a portable turntable, the combination of a frame provided with tracks adapted to receive a truck, rear transport wheels mounted on said frame, means whereby said frame may be pivotally supported with said wheels clear of the ground, front wheels pivotally connected to the forward end of the frame, and means for locking said front wheels in position to travel in an arc about said pivotal support. 100

3. In a portable turntable, the combination of a frame provided with truck receiving track rails, a pair of carrying wheels pivotally connected with the forward end of said frame, means for pivotally supporting said frame intermediate its ends so that the frame may be swung horizontally about said supporting means, and rear carrying wheels mounted on said frame and upon which the frame may be transported, said rear carrying wheels and said pivotal supporting means being operable in alternation only. 110

4. In a portable turntable, the combination of a frame providing truck receiving tracks, rear wheels mounted on said frame, pivotal supporting means connected with the frame, means whereby the frame may be lifted and supported upon said supporting means with said wheels clear of the ground, and a plurality of front wheels pivoted on said frame. 125

5. In a portable turntable, the combination of a frame adapted to receive a loaded truck, rear transport wheels therefor, means for raising and pivotally supporting said frame with said wheels clear of the ground, and front supporting wheels pivotally connected to the frame, said front wheels being adapted to travel in an arc about said pivotal support for turning purposes and to be disposed in parallelism for transport purposes.
6. In a portable turntable, the combination of a frame adapted to receive a loaded truck, rear transport wheels mounted on said frame, an axial support for said frame adapted to take the weight off said rear
- transport wheels and about which the frame may be swung for turning purposes, and front wheels pivoted to said frame and adapted to travel in an arc about said axial support.
7. In a portable turntable the combination of a frame structure adapted to receive and support a truck, front and rear transport wheels upon which said frame may be transported, and means independent of the rear transport wheels for pivotally supporting said frame so as to permit swinging movements thereof about a vertical axis, said front wheels being adapted to travel in an arc about said axis as a center.

FRANK E. MINER.
